US00D831764S

(12) **United States Design Patent** (10) Patent No.: **US D831,764 S**
(45) Date of Patent: **** Oct. 23, 2018**

(54) **FLEXIBLE STRAP WITH A DUAL STITCH PATTERN**

(71) Applicant: **Fitness Anywhere LLC**, San Francisco, CA (US)

(72) Inventors: **Randal A Hetrick**, San Francisco, CA (US); **Mauricio Hernan Delgado**, San Anselmo, CA (US)

(73) Assignee: **FITNESS ANYWHERE LLC**, San Francisco, CA (US)

(**) Term: **15 Years**

(21) Appl. No.: **29/587,147**

(22) Filed: **Dec. 9, 2016**

(51) LOC (11) Cl. **21-02**

(52) U.S. Cl.

USPC **D21/694**

(57) **CLAIM**

The ornamental design for a flexible strap with a dual stitch pattern, as shown and described.

DESCRIPTION

FIG. 1 is a perspective view of the flexible strap with a dual stitch pattern;

FIG. 2 is a front view of the flexible strap with a dual stitch pattern of FIG. 1;

FIG. 3 is a back view of the flexible strap with a dual stitch pattern of FIG. 1;

FIGS. 4 and 5 are the left and right side views of the flexible strap with a dual stitch pattern of FIG. 1; and,

FIGS. 6 and 7 are the top and bottom views of the flexible strap with a dual stitch pattern of FIG. 1.

The broken line shown in the figures are for the purpose of illustrating portions of the flexible strap with a dual stitch pattern which form no part of the claimed design.

1 Claim, 3 Drawing Sheets
